ATTORNEY.

UNITED STATES PATENT OFFICE.

MYER L. VICTORIUS, OF NEW YORK, N. Y.

METHOD OF COUNTING HOSIERY.

Application filed June 28, 1922. Serial No. 571,563.

To all whom it may concern:

Be it known that I, MYER L. VICTORIUS, a citizen of the United States, residing at New York city, county of New York, and State 5 of New York, have invented a new and useful Improvement in Methods of Counting Hosiery, of which the following is a full, clear, and exact description, reference being had to the accompanying drawings, which 10 form a part of this specification.

This invention relates to a method of handling hosiery to facilitate the counting thereof and avoid mistakes in the counting.

15 In mills of which I have personal knowledge the knitters usually bundle the stockings as they are cast off from the knitting machines, and these bundles are then passed to the loopers.

20 These bundles usually contain twenty-four stockings or a dozen pairs of stockings. The operators frequently make miscounts and frequently pass to the loopers bundles containing more or less than the stipulated 25 number of stockings.

As most of the work is done under the piece work system, such mistakes cause considerable annoyance to the loopers and other operators through whose hands the stockings 30 pass in the process of manufacture after the knitters pass them along, as well as to the clerks who have charge of the work records.

The above annoyances are very aggravating, but not nearly so aggravating as when mistakes are made in the count of special orders, such as small orders of special design, size and yarn. When such mistakes are made, it necessitates the setting 40 up of the different machines to make a few stockings to complete the order if the count is short, or if too many stockings have been made, such stockings are frequently left on the hands of the manufacturers.

45 The knitters who usually count and bundle the stockings have a number of machines under their supervision and are required to watch the work done by the machines, keep the machines supplied with 50 yarn, start the machines after a completed stocking has been cast off, and pick up the stockings cast off. It will, therefore, be seen that the knitters must be on the alert at all

times to keep the machines in operation and that their eyes must be on the move from 55 machine to machine even under normal conditions, and are therefore very liable to make miscounts when bundling.

The object of my invention is to provide 60 a method and means for counting the stockings for making up a bundle, whereby the human element as far as the counting is concerned is entirely eliminated, and thereby insure proper counting.

I accomplish this by placing a rack accessible to each knitter, having a plurality of pegs thereon, the number thereof being dependent upon the number of stockings desired in the bundles. I preferably provide these racks with pegs on which the 70 stockings may be hung by passing the looping openings over the pegs and so arrange the pegs that all of the stockings for making up a bundle can be tied together while so supported and simultaneously removed, 75 or simultaneously removed and then tied.

The precise nature of my invention will be best understood by reference to the accompanying drawings, which will now be described, it being premised, however, that 80 changes may be made without departing from the spirit and scope of my invention as defined in the appended claims.

Fig. 1 of the drawings is a perspective view of one form of apparatus illustrating 85 my invention.

Fig. 2 is a face view of a portion of the rack shown in Fig. 1.

Fig. 3 is an end view of the rack shown in Fig. 1.

Fig. 4 is a perspective view of a bundle of stockings.

My preferred form of rack as illustrated in the drawings comprises a base *b* having an upper row of pegs *c* and a lower row *d*, 95 the pegs in one row being in staggered relation to those in the other row, so that the stockings for making up a bundle will be relatively close to each other when hung from the rack, but sufficiently spaced to 100 clearly indicate if one of the pegs has not been supplied with a stocking.

The pegs in the form shown are preferably made of wood and are inserted into openings in the base *b* at about an angle of 105 forty-five degrees to the surfaces of the

base, and when so positioned the base is so supported that its front will be in a vertical plane.

As the stockings are cast off the knitting machines, the operator picks them up and hangs one stocking on a peg by passing the toe opening *e* of the stocking over a peg, and when the pegs have been filled, the stockings are formed into a bundle and tied about the middle of the stockings.

The stockings may be tied into a bundle such as shown in Fig. 4 while on the pegs, and then all withdrawn, or the stockings may be grasped by the knitter, withdrawn from the pegs and then tied into a bundle.

The rack shown is provided with twenty-four pegs to form bundles of a dozen pairs of stockings.

I have found that by spacing the pegs one and one-half inches apart in the rows, and spacing the rows two and one-fourth inches apart, the stockings will be close enough to be bundled while on the pegs and still sufficiently spaced to note at a glance whether any of the pegs are empty.

I preferably use pegs made of hard wood which can readily be made smooth and which will retain their smoothness in use, although the pegs or hooks may be made in other shapes and from other material.

The base may also be made of a different shape and of different material and may be supported in any desired manner.

The advantages of my invention result from the provision of a method and apparatus for bundling hosiery, whereby the stockings are properly positioned for bundling as well as insuring the proper number of stockings for each bundle without any mental effort on the part of the operator. Further, by the use of my invention, a saving in time and labor is effected which results in increased production, giving greater earning power to operatives and eliminating fatigue to a considerable extent.

Having now fully described my invention, what I claim and desire to protect by Letters Patent is:

1. The method of counting stockings comprising the steps of hanging stockings in a prearranged order and when such order has been completed bundling the stockings, and thereby insuring bundles having the prearranged number of stockings without counting. 50

2. The method of counting and bundling stockings comprising the steps of hanging the stockings by their unlooped toes in a prearranged order as they are cast off from a knitting machine, tying the stockings 60 while so hung, and then removing the stockings from their supports.

3. The method of counting stockings by indirect or automatic computation comprising arranging the stockings one at a time 65 after they are cast off from the machine in a predetermined order within a predetermined space until said order is completed and said space fully occupied, and then removing all the stockings from such space 70 while maintaining them associated, thereby dispensing with the necessity of computing the number of stockings per bundle while insuring against mistakes involved in erroneous computation. 75

4. The method of bundling stockings with a prearranged number of stockings in the bundles, comprising the steps of successively arranging the stockings in a prearranged order over a given space, while 80 maintaining the stockings separated from each other at a portion along their length, and when said space has been filled with stockings forming the stockings into a bundle. 85

In testimony of which invention, I have hereunto set my hand, at New York, N. Y., on this 23rd day of June, 1922.

MYER L. VICTORIUS.
